UNITED STATES PATENT OFFICE

162,678

LAVATORY FITTING

Peter Muller-Munk, Pittsburgh, Pa., assignor to
Eljer Co., Ford City, Pa.

Application June 29, 1948, Serial No. 147,261

Term of patent 14 years

(Cl. D4—3)

To all whom it may concern:

Be it known that I, Peter Mueller-Munk, a citizen of the United States, residing at Pittsburgh, Pennsylvania, have invented a new, original and ornamental Design for a Lavatory Fitting, of which the following is a specification, reference being had to the accompanying drawing, forming part thereof.

Figure 1 is a top plan view of a lavatory fitting showing my new design;

Figure 2 is a side elevational view thereof; and Figure 3 is a view thereof taken on the lines 3—3 of Figure 2.

I claim:

The ornamental design for a lavatory fitting, as shown.

PETER MULLER-MUNK.
